ASSIGNORS TO MORGAN CONSTRUCTION COMPANY, OF WORCESTER, MASSACHUSETTS, A CORPORATION OF MASSACHUSETTS.

ROD-Straightening Machine.

1,170,242.

Specification of Letters Patent. Patented Feb. 1, 1916.

Application filed February 17, 1913. Serial No. 748,806.

To all whom it may concern:

Be it known that we, JEROME R. GEORGE and VICTOR E. EDWARDS, both citizens of the United States, residing at Worcester, in the 5 county of Worcester and Commonwealth of Massachusetts, have invented a new and useful Improvement in Rod-Straightening Machines, of which the following, together with the accompanying drawing, is a specification.

Our invention relates to rod straightening machines of that type which includes two sets of rollers between which a rod to be straightened is passed.

An object of the invention is to construct a rod straightening machine in such manner that the straightening rollers may be easily and quickly released from their supports for purposes of removal or replacement.

A further object is to provide a machine which will be simple in construction and which will, at the same time, be efficient.

In the accompanying drawing, Figure 1 25 is a side elevation of a rod straightening machine constructed in accordance with our invention, and Fig. 2 is a plan view of the machine shown in Fig. 1.

Like reference characters refer to similar parts in both figures.

The body or frame of the machine includes a lower portion or base 1 and an upper portion or cap 2, the base 1 being mounted in any suitable manner upon foundations 3. Two straightening rollers 4 and 5 are mounted at their opposite ends in bearings carried by the sides of the base 1. Each side of the base 1, shown in Fig. 1, is formed to provide two parallel vertical opposed 35 guideways 6 in which a bearing 7 may slide vertically. The portion of the side of the base 1 between the two guideways 6 forms a horizontal support 8 for the bearing 7 to rest upon. The lower corners of the bearing 45 are removed to obviate the necessity of fitting them into the angles formed by the guideways 6 and the supporting face 8 and, further, so that accumulations of matter at these points will not interfere with the 50 proper seating of the bearing. A bearing 9 for the end of the roller 5, shown in Fig. 1, is similarly mounted upon a supporting face 10 and between vertical guideways 11 formed in the base 1, and similar bearings are also

provided at the other end of each of the 55 rollers 4 and 5.

A bar 12 is adjustably supported under each side of the base 1 by rods 13, being held in desired position on the rods 13 by means of nuts 13'. The two bars 12 support the 60 weight of the upper rollers 14, 15 and 16. Between the end of the roller 14, shown in Fig. 1, and the supporting bar 12, thereunder is a vertical rod 17 extending through the corresponding side of the base 1. The 65 upper end of this rod carries a saddle 18 in which rests a journal 19 formed at the end of the roller 14 and in which this journal may rotate. The lower end of the rod 17 slides freely in an opening in the bar 12. 70 The rod 17, however, carries a collar 20 secured adjustably in position on the rod by a nut 21 and the bar 12 carries an opposed collar 22 surrounding the rod 17, a spiral spring 23 being interposed between the collars 20 and 22 so as to provide a yieldable support for the rod 17 and the roller 14. Each end of each of the upper rollers 75 14, 15 and 16 is supported in a similar manner.

If a rod to be straightened be heavy and rigid, the mere weight of the upper rollers 14, 15 and 16 would not be sufficient to straighten the rod. It is necessary, therefore, to prevent upward motion of the upper 85 rollers beyond a certain limit. The journal 19 of the roller 14 is held by the saddle 18 against an upper bearing 24, slidably supported in vertical opposed guideways 25 formed in the corresponding side of the 90 upper portion or cap 2 of the frame of the machine. The bearing 24 carries a thrust member 26 in line with a rod 27 which is in threaded engagement with the upper portion 2 of the frame of the machine. It is 95 clear that by turning the rod 27 its vertical position may be adjusted to vary the uppermost position of the roller 14. The rod 27 is turned by means of a worm gear 28 operated by a rod 29 carrying a worm 30 and 100 supported in brackets 31 and 32. The rod 29 carries a second worm 33 engaging a second worm gear 34 acting to adjust vertically the bearing for the other end of the roller 14. By turning a hand wheel 35 attached to 105 the rod 29, the upper bearings for both ends of the rollers are adjusted simultaneously. Similar bearings and adjusting means there-

for are provided for each of the other upper rollers 15 and 16.

When a rod is being passed through the machine in order to straighten it, the entire pressure of such rod upon the upper set of rollers 15 and 16 is, of course, in an upward direction and the position of the bars 12 and the compression of the springs 23 are adjusted so as to hold the upper rollers firmly against the bearings 24.

The base 1 and the upper portion 2 of the frame of the machine are secured together by rods 36 pivoted to the base 1 and lying normally in grooves 37 in the upper portion 2 of the machine, each rod 36 being supplied with a collar or washer 38 held against the upper face of the upper portion 2 of the frame of the machine by a wedge 39 passing through a slot 40 in the upper end of the rod. By driving out the wedges 39 sufficiently to loosen them, the rods 36 may be swung outwardly, as shown in Fig. 1, thus releasing the upper portion 2 of the frame of the machine. This upper portion 2 may then be lifted from the base 1, leaving both sets of rollers with all their bearings supported upon the base 1, the bearings 24 sliding from their guideways 25 as the upper portion 2 of the frame is raised. Inasmuch as the bearings 24 and saddles 18 carrying the upper rollers, and the bearings 7 and 9 carrying the lower rollers, do not extend through arcs of more than 180°, each bearing and roller may now be lifted from the machine. One end of each roller is provided with grooves 41, or is otherwise suitably formed, to be engaged by means for driving the rollers in any desired manner.

It will be noticed that each pair of guideways provided for the various bearings forms a recess which opens into a space along the dividing line between the lower and upper portions of the corresponding side of the frame. This is an important feature of the invention inasmuch as it is only necessary to separate the two portions of the frame in order to free the different

bearings so that they may be removed immediately and easily from their various positions in the frame. It is obvious that this feature would be present in a machine in which each pair of guideways was extended to a common plane, but it is preferable to form such guideways only sufficiently long to accommodate properly their respective bearings, and it will usually be found desirable to provide a common space between the two portions of each end of the frame into which the various recesses formed by the pairs of guideways may open. Provision of such common space is advantageous not only in reducing the weight of the machine, but also in reducing the lengths of the guideways and thus the amount of labor necessary in forming and fitting them.

Having thus described our invention, what we claim as new and desire to secure by Letters Patent is:

1. In a rod straightening machine, a base portion, a set of rollers carried by said base portion, a detachable cap portion, a set of rollers disposed within said cap portion, a yielding support for each of said last mentioned rollers, and adjustable means, carried by said base portion, for sustaining said yielding supports.

2. A rod straightening machine including a frame having a base portion and a detachable cap portion, a set of rod straightening rollers carried within said cap portion, a support for each of the rollers, springs for said supports to rest upon, an adjustable support for said springs, whereby the forces of the springs may be simultaneously adjusted, said support being carried by said base portion and a set of cooperating rod straightening rollers carried within said base portion.

Dated this 12th day of February, 1913.

JEROME R. GEORGE.

VICTOR E. EDWARDS.
